UNITED STATES PATENT OFFICE.

JOSEPH B. HOLDEN, OF SYRACUSE, NEW YORK, ASSIGNOR TO REMINGTON TYPEWRITER COMPANY, OF ILION, NEW YORK, A CORPORATION OF NEW YORK.

TYPEWRITING MACHINE.

Application filed January 29, 1923. Serial No. 615,474.

To all whom it may concern:

Be it known that I, JOSEPH B. HOLDEN, citizen of the United States, and resident of Syracuse, in the county of Onondaga and State of New York, have invented certain new and useful Improvements in Typewriting Machines, of which the following is a specification.

My invention relates to typewriting machines and, generally stated, more particularly to improved means for ensuring that the machine is in proper condition to be received within its inclosing case before the case is closed.

To the above and other ends which will hereinafter appear, my invention consists in the features of construction, arrangements of parts and combinations of devices set forth in the following description and particularly pointed out in the appended claims.

In the drawings, wherein like reference characters indicate corresponding parts in the different views,

Figure 1 is a fragmentary fore-and-aft vertical sectional view of a Remington portable machine embodying my invention, the machine being shown in condition for use and the platen locked in case shifted position.

Figure 2 is a like view of the same, the machine being shown collapsed and inclosed within its carrying case.

Figure 3 is a fragmentary detail top plan view showing a part of the case shifting mechanism and some of the associated parts.

Figure 4 is a detail perspective view of the case shift lock release lever.

In the drawings I have omitted parts of the machine unnecessary to an understanding of my invention in its embodiment therein.

My invention relates more particularly to light portable machines and is shown in the present instance embodied in a Remington portable machine which in many respects is like the machine shown in the following patents and application:

A. W. Smith, No. 1,342,513, dated June 8, 1920; J. B. Holden, No. 1,386,256, dated Aug. 2, 1921; H. E. Bridgwater, Sr. No. 553,732, filed Apr. 17, 1922.

In the Remington portable machine the carriage is supported against movement from its normal or lower case position by the cover

of the inclosing case when the latter is closed. This prevents the carriage from shifting 55 backward and forward when the machine is being transported in its case, thus preventing injury to the machine which might result from such shifting of the carriage.

If, however, the operator should leave the 60 carriage locked in its shifted position it would interfere with and prevent the cover from being closed. Any forcible attempt to close the cover at this time might result in 65 injury to the machine or to the cover, or both.

In the application of Charles E. Smith, Sr. No. 538,267, filed Feb. 21, 1922, a construction is disclosed by which these objections are overcome and means are provided to ensure 70 the proper return of the carriage to normal position before the cover is closed, and thereafter the case shift locking means are rendered ineffective so long as the machine is in condition to be inclosed within its casing. 75 Furthermore, the act of expanding the machine, or rendering it in condition for use, is effective to automatically withdraw the means by which the case shift locking means are rendered ineffective, so that such locking 80 means are again in condition for use.

The same general objects are attained by my present construction without modifying the structural features of the Remington portable machine, except by the simple addition of a part or two, as will hereinafter appear.

The frame of the machine comprises an outer sheet metal frame 1 and an inner sheet metal frame 2 attached to the frame 1, and 90 by which latter frame the various working parts of the machine are supported. A series of segmentally arranged type bars 3 are mounted in guide slots of a type bar segment 4, secured to the inner frame 2 and carrying 95 a pivot wire 5 on which the type bars are mounted. Each type bar has a heel with segmentally arranged gear teeth 6, with which similar teeth 7 on a companion sub-lever 8 are adapted to mesh. The sub-levers 8 are 100 pivoted on a pivot wire 9 carried by a suitably fixed slotted support or segment, not shown. The forward end of each sub-lever 8 is pivoted to a depending link 10, which in turn is pivoted to a second sub-lever 11, fulcrumed at its forward end on a sheet metal 105

combined guide comb and fulcrum plate, designated as a whole by the reference numeral 12. This plate is secured in place at its ends by screws 13 that are received in 5 tapped openings in ears 15 on the side plates of the inner frame 2.

Each sub-lever 11 is connected to a depending link 17, which in turn is connected to a key lever 18, pivoted on a pivot wire 19. 10 The rear end of each key lever is guided by and held on its pivot by a guide comb 20 which supports the pivot wire on a fixed part of the machine, whereas the forward end portion of each key lever extends through a 15 guide slot 21 in the forward guide comb 12.

The type bars are adapted to be turned on their pivot wire 5 from the inoperative position shown in Fig. 2, where they remain collapsed relatively to the remainder of the machine on a fixed type rest *a*, to the operative position, or position of use, indicated in Fig. 1. In this last mentioned position the type bars are expanded upwardly from the body of the machine, and each is in a position to 20 be moved rearwardly and downwardly to the printing position, and to strike against the top of a platen 22 when the companion printing key is depressed to actuate its lever 18. The hand actuated means operable at 25 will, and by which the type bars are turned from their inoperative position shown in Fig. 2 to their operative position shown in Fig. 1, comprises a rock shaft 23 mounted at its ends in the side plates of the inner frame 2. One end portion of the shaft has the usual crank arm (not shown) which carries 30 a finger piece operable from the right-hand side of the machine, and which may be locked against movement in either extreme 35 position to which it may be shifted, as usual. The hand controlled rock shaft 23 carries two crank arms 24, one near each side of the machine. The free end of each crank arm is pivoted at 25 to a link 26, which in turn is 40 pivoted at its upper end, as at 27, to a shiftable frame. This frame is designated as a whole by the reference numeral 28, and extends transversely across the machine to points near the sides thereof. The frame 28 is formed with depending guide arms 29 that are mounted to move up and down in 45 companion grooved guides 30 carried by the type bar segment 4. The frame 28 thus mounted for vertical shifting movement 50 from the Fig. 1 to the Fig. 2 position, and vice versa, carries a segmental pad 31 arranged beneath the type bars and co-operative therewith to control the movements of the type bars around their pivot 55 to either of the two positions shown. Each of the type bars carries a lower case type 32 and an upper case type 33, and in the Remington portable machine a case shifting movement of the platen may be effected to bring either set of types into use.

In Figs. 1 and 2, it will be seen that a sheet metal case shift frame extends fore and aft of the machine and comprises side plates 34. Each of these plates is pivoted at its forward end, as at 35, to a depending link 36 mounted on a pivot pin 37 projecting inwardly from a side plate of the frame 2, and prevented from accidental detachment from its pivot by a cotter pin 38. The rear end portion of each plate 34 is bent to form a 70 horizontally disposed flange 39 to which is secured, by screws 40, a casting 41. This casting is pivoted at 42 to upright crank arms 43, carried by a rock shaft 44 received at its ends in bearing openings in the side 75 plates of the frame 2. The casting carries sheet metal grooved tracks 45 and 46 which receive bearing rollers 47 that also coact with the grooved tracks 48 and 49 of a carriage bed 50 which supports the platen 22. 80 The entire carriage with its platen is thus supported to travel laterally over the support or casting 41, and to receive a bodily fore and aft shifting movement with the case shift frame of which the support 41 forms a part. Suitable stops *b* and *c* are employed to limit the case shifting movements of the parts, and springs 51 return the shifted parts to normal or lower case position when they are not held in the upper case 85 position against the force of said springs.

In the present construction the key actuated means for controlling the case shifting movements of the parts are substantially the same as those disclosed in the above mentioned application of Herbert E. Bridgewater, and comprises a case shift key lever 54 provided with a key 55 and fulcrumed on the pivot wire 19. This key lever is guided at its forward end portion in a guide slot 100 in the comb plate 12, and is returned to normal position by a spring 54^a. The lever 54 has a depending projection 56 co-operative with the roller 57 on a headed pin 58 projecting laterally from a crank arm 59. This crank arm projects upwardly and rearwardly from a rock shaft 60 that extends transversely of the machine and is mounted at its reduced ends in bearing openings in the side plates of the inner frame 2. A centrally located arm 61 on the rock shaft is pivoted at 62 to a rearwardly extending link 63, connected by a screw 64 to a forwardly extending arm of a bracket 65, secured by screws 66 to the case shift frame. Another 110 shift key lever (not shown) is also employed on the other side of the machine to coact with a second crank arm on the rock shaft 60 to rock it in the same manner as the shift key lever 54. A depression of the shift key lever 54, or the corresponding lever at the opposite side of the machine, is effective to rock the shaft 60, and through the link 63 shift the case shift frame and the parts carried thereby back from the Fig. 2 to the 115 120 125 130

Fig. 1 position. A shift lock key 67 is carried by one arm of an angular lever 68 which is pivoted at 69 to the lever 54 on the outer side thereof. The lever 68 has a second arm 5 at the other side of its fulcrum or pivot which terminates in a hook-like engaging or locking member or catch 70. The pivot 69 which unites the levers 68 and 54 is in the nature of a shouldered screw bolt secured 10 by a nut 71 to the lever 54 and forming a pivot bearing for the lever 68. A spring 72 is coiled around the shank of the screw bolt and has one free end 73 thereof turned over and bearing against the bottom edge of the 15 lever 68; its other free end 74 bearing against the upper edge of the lever 54. The force of this spring is exerted to turn the lever 68 on its pivot 69 to the Fig. 2 position, and to normally maintain it relatively 20 to the lever 54 in the position shown in this figure. A lug 75 formed on and extending laterally from the lower edge of the key carrying arm of the lever 68 projects under the lever 54, and co-acts therewith to limit the 25 return movement of the lever 68 relatively to the lever 54.

A sheet metal locking plate or member 76 is secured in front of the comb plate 12 at the left-hand end portion thereof. One of the screws 13 secures the upper end of the member 76 in place, whereas a screw 77 connects said member intermediate its ends to the plate 12; the lower end portion of the member 76 sloping forward away from the comb plate. It will be seen that this plate is mounted to the left of the slot in the comb plate 12 that receives the shift lever 54 and that its lower engaging edge 78 extends forward of the lower edge of the comb plate. Pressure applied directly to the shift lock key 67 will first turn the lever 68 on its pivot 69 until the hook-like end 70 of said lever bears against the front face of the plate 76. Since the lever 68 can turn no further at this time the pressure exerted on the key 67 will carry the lever 54 down with it until the bill of the hook reaches the edge 78 of the plate. The hook will then be forced beneath said edge 78, and engaging 50 the latter will prevent a return movement of the lever 68, shift lever 54 and the parts controlled thereby, and will lock the carriage in its case shifted position. In order to release the locking lever 68 and enable 55 the parts to return to normal position, it is merely necessary with the parts thus far described, to depress the shift key 55. This relieves the engaging pressure exerted by the bill of the hook against the edge 78 of the locking plate. The lever 68 being thus freed from further restraint will be returned by its spring 72 to normal position relatively to the lever 54. This results in withdrawing the bill of the hook 70 from beneath the edge 78 of the locking plate,

and when pressure of the operator's finger is released from the depressed shift key 55 the key lever 54 and the parts controlled thereby are returned to normal position by the returning springs 54^a and 51. 70

The Remington portable machine is provided with a carrying case in which the machine may be inclosed before transporting it. The inclosing case includes a baseboard 79 on which the machine is fixedly secured, and a detachable cover 80 having a rear wall 81. Rearwardly projecting fingers 82 are secured to the baseboard and are adapted to enter openings in plates 83 secured to the back wall 81 of the cover. 75

When the machine is collapsed, the carriage properly centered and in normal or lower case position, the cover may be aligned with the baseboard in the rear thereof with the projections 82 extending in the openings 85 in the plates 83. The cover may then be given a pivotal movement on said projections 82, resulting in swinging the cover forward and down around the rear edge of the baseboard to inclose the machine. The rear wall 81 of the cover, as usual, is provided with contacts 84 which, in the present instance, are in the nature of rubber blocks secured to and projecting inwardly from the rear wall 81 near each side wall. These contacts are aligned with the end plates 85 of the carriage when the latter is centered on the machine. The purpose of these contacts is to bear against the end plates 85 of the carriage when the cover is closed, and support the weight of the carriage in normal or lower case position, and prevent the carriage from shifting from said position while the machine is being carried in the case, rear end lowermost. This prevents the carriage from shifting back and forth while the machine is being transported in its case, and prevents the resultant injury to the machine that might follow from such shifting movement of the carriage. However, it will 100 be understood from a consideration of Figs. 1 and 2 that if the operator should leave the case shifting mechanism locked as indicated in Fig. 1, the carriage would be held in its rearmost shifted position; increasing 105 the lengthwise dimensions of the machine at this point. This would result in the rear ends of the plates 85 of the carriage being maintained in the path of the projections 84 on the cover and prevent the cover from 110 being closed. The use of any considerable force to close the cover at this time might result in injury to the machine or to the cover, or to both. 115

The purpose of my present invention in the main is to overcome the difficulty pointed out above and render it impossible to injure the machine or its cover by providing simple automatically operating means that may be readily incorporated in the machine for 120 125 130

releasing the case shift locking means preliminary to inclosing the machine, and thereafter render the case shift lock ineffective until such time as the machine is again in condition for use. It will of course be understood that it is necessary to collapse the machine before it can be inclosed in its case. I utilize the means for collapsing the machine to automatically effect a release of the case shift lock if it should be held in locked position, and also to thereafter render ineffective such locking means until the machine has been expanded and is again in condition for use. Thus a releasing lever, 15 designated as a whole by the reference numeral 86 and shown in detail in Fig. 4, is apertured at 87 for pivotal mounting on an interiorly threaded stud 88 (see Fig. 3) secured to and projecting in from the left-hand side plate of the inner frame 2. A headed screw 89 is threaded into the stud 88 and has its head overlapping the lever 86 to hold it on its pivot. A washer or spacing sleeve 90 surrounds the stud, and is 20 interposed between the lever 86 and the left-hand side plate of the inner frame. The lever 86 thus mounted for pivotal movement extends fore and aft of the machine and passes through a cut-out in the lower 25 edge of the comb plate 12. The forward end portion of the lever 86 is bent to the left to provide a contact or engaging member 91 which crosses the plane of movement of the lug 75 on the key carrying arm of the case shift locking lever 68, and in certain circumstances is adapted to coact therewith, as will presently appear. The rear end portion of the lever 86 is formed with a yoke-like portion 92 that straddles the adjacent shift lever 54, and co-acts therewith to guide the releasing lever in its pivotal movements. The rear end 93 of the releasing lever 86 is slightly off-set to the right to bring it into the plane of movement of a contact device, in the nature of a pin 94, fixed to the left-hand link 26 by which the type bars are shifted to and from collapsed position. Should the operator before inclosing the machine inadvertently 30 leave the carriage locked in its case shifted position shown in Fig. 1, where ordinarily it would prevent the cover from being closed, no injurious results can follow in the present construction. Thus, as a necessary preliminary to inclosing the machine, the shaft 23 must be turned to collapse the type bars. The act of doing this moves the left-hand collapsing link 26 from the Fig. 1 to the Fig. 2 position. This movement of the left-hand link 26 carries the pin 94 thereon through the path indicated by the series of dotted circles in Fig. 1 to the Fig. 2 position. This brings the pin 94 down against the rear end 93 of the releasing lever 86 and 35 tilts it on its pivot 88 from the Fig. 1 to the

Fig. 2 position, elevating the front end of said releasing lever to the position shown in Fig. 2. If the locking lever 68 at this time be locked down, as has been supposed, then the result will be that it will be shifted 70 around its pivot 69 to disengage its hooked end 70 from the locking plate 76. As soon as such disengagement takes place the spring 72 is effective to return it to normal position relatively to the shift lever 54, and the latter will be returned to normal position by its spring 54^a. This enables the springs 51 to move the shift frame and carriage forward to normal or lower case position, where the end plates 85 of the carriage no longer 80 offer obstructions to prevent the cover from being closed.

It will be seen that so long as the type bars remain collapsed, the forward end of the releasing lever 86 is held against being 85 moved down from the position shown in Fig. 2. It follows therefore that should the operator depress the shift lock key 67 after the type bars are collapsed, then the lug 75 on the other arm of the locking lever from engaging beneath the lower edge 78 of the 90 locking plate 76 and locking the parts in case shifted position. Therefore, the automatic actuation of the release lever 86 is effective to release the case shift locking means if they be locked, and thereafter prevents the operator from locking the carriage in case shifted position until the type bars are expanded to place the machine in condition for use. If the carriage be not locked in its case shifted position when the type 105 bars are collapsed, then the release lever will prevent this from being done until the type bars are expanded to place the machine in condition for use. The act of expanding the bars removes the pin 94 from the releasing lever 86, and the latter is no longer effective to prevent the case shift lock from operating until the type bars are again collapsed.

It will be understood that the rear end 115 portion of the releasing lever 86 being heavier than the forward end thereof will tend to carry the rear end of said lever down until the cross bar 92^a of the yoke 92 coacts with the lever 54 and arrests further pivotal movement of the releasing lever. This will leave the contact 91 on the releasing lever normally extending into the path of the lug 75 on the locking lever 68 and forward of the pivot 69 of the latter. When 120 the parts are normally disposed and the type bars are expanded, a depression of the locking key 67 will merely result in moving the releasing lever 86 to the position shown in Fig. 1 without interfering with the en- 125

gagement of the locking lever with the locking plate 76. If, however, the type bars be collapsed as shown in Fig. 2, then the pin 94 will be brought into the path of the releasing lever 86 and the latter will be held against movement, and with the forward end thereof interposed in the path of the lug 75 on the key carrying arm of the case shift locking lever, as shown in Fig. 2, and will prevent the carriage from being locked in shifted position.

From the foregoing description it will be understood that my invention may be readily incorporated in Remington portable machines without modifying the structural features of said machines as they now exist, except by the addition of the pin 94 and the releasing lever 86.

What I claim as new and desire to secure by Letters Patent, is:—

1. In a typewriting or like machine, the combination of case shift mechanism including a locking lever for locking the shiftable part in shifted position and having an engaging member at one side of its fulcrum and a key at the other; a collapsible part of the machine; and a releasing lever operative on said locking lever at the key carrying side thereof and actuated by a movement of said collapsible part to collapsed position to release the locking lever from locked position.

2. In a typewriting or like machine, the combination of case shift mechanism including a locking lever for locking the shiftable part in shifted position and having an engaging member at one side of its fulcrum and a key at the other; a collapsible part of the machine; and a releasing lever operative on said locking lever at the key carrying side thereof and actuated by a movement of said collapsible part to collapsed position to release the locking lever from locked position, said releasing lever being held in the path of the key carrying side of the locking lever so long as the collapsible part remains collapsed and preventing a locking of the shiftable part in case shifted position.

3. In a typewriting or like machine, the combination of case shift mechanism including a case shift key lever and an angular case shift-locking lever pivoted on the case shift lever and having a key on one arm and an engaging member on the other; a collapsible part of the machine; and a releasing lever moved to effective position by the movement of the collapsible part to collapsed position and is operative on the key carrying arm of the locking lever to release the latter from locked position.

4. In a typewriting or like machine, the combination of case shift mechanism including a locking lever for locking the shiftable part in case shifted position and having a key on one arm and an engaging member on the other arm; a part of the machine

movable from an expanded position for use to a compact position; controlling means for thus moving said last mentioned part; and a releasing lever that extends fore and aft of the machine from said controlling means to the key carrying arm of said locking lever and is operative thereon to release the locking lever when said controlling means are shifted to compact the part controlled thereby.

5. In a typewriting or like machine, the combination of case shift mechanism including a locking lever for locking the shiftable part in case shifted position and having a key on one arm and an engaging member on the other arm; collapsible type bars; means including a link for collapsing said type bars; and means controlled by said link and acting on the key carrying arm of said locking lever for shifting it to releasing position.

6. In a typewriting or like machine, the combination of case shift mechanism including a locking lever for locking the shiftable part in case shifted position and having a key on one arm and an engaging member on the other arm; collapsible type bars; means including a link for collapsing said type bars; and a releasing lever acted on at one end by said link and at the other end acting on the key carrying end of said locking lever to release it from locked position and prevent it thereafter from locking the shiftable part in shifted position so long as the type bars remain collapsed.

7. In a typewriting or like machine, the combination of case shift mechanism including a locking lever for locking the shiftable part in case shifted position, the shiftable part when thus locked preventing the carrying case of the machine from being closed, said locking lever having a key on one arm and an engaging member on the other arm; a part of the machine movable from an expanded position for use to a compact position and when in said expanded position preventing said carrying case from being closed; controlling means for compacting said compactible part; and a releasing lever controlled by an extending from said controlling means to the key carrying arm of said locking lever and effective to release the latter if locked and thereafter prevent it from locking so long as the controlling means maintain the compactible part compacted.

8. In a typewriting or like machine, the combination of case shift mechanism including a locking lever; a collapsible part of the machine; means for collapsing said part; a releasing lever co-operative with said locking lever; and a contact on said collapsing means disconnected from and out of co-operative relation with said releasing lever when said collapsing means maintain the

collapsible part in expanded position for use and moved into contactive engagement with said releasing lever when said collapsing means moves the collapsible part 5 to collapsed position and thereby control said releasing lever and the co-operative locking lever.

Signed at Syracuse, in the county of Onondaga and State of New York, this 25 day of January, A. D. 1923.
